Wm. Mason,
Inventor,
By Atty. J. C. Earle

UNITED STATES PATENT OFFICE.

WILLIAM MASON, OF NEW HAVEN, CONNECTICUT, ASSIGNOR TO THE WINCHESTER REPEATING ARMS COMPANY, OF SAME PLACE.

MAGAZINE FIRE-ARM.

SPECIFICATION forming part of Letters Patent No. 278,987, dated June 5, 1883.

Application filed May 7, 1883. (No model.)

To all whom it may concern:

Be it known that I, WILLIAM MASON, of New Haven, in the county of New Haven and State of Connecticut, have invented a new Improvement in Magazine Fire-Arms; and I do hereby declare the following, when taken in connection with the accompanying drawings and the letters of reference marked thereon, to be a full, clear, and exact description of the same, and which said drawings constitute part of this specification, and represent, in—

Figure 1, a sectional side view of the parts in the position for firing; Fig. 2, the same, the breech-piece open; Figs. 3 and 4, sectional side views, showing, respectively, modifications of the arm with the breech in the closed and open positions; Fig. 5, a transverse section on line *w w*, looking forward; Fig. 6, a transverse section on line *x x* of Fig. 3, looking rearward; Fig. 7, a transverse section on line *y y* on Fig. 3, looking forward; Fig. 8, a transverse section through line *z z*.

This invention relates to an improvement in that class of magazine-arms in which a longitudinally-movable breech-piece is arranged in axial line with the barrel, and beneath the barrel a magazine, combined with a carrier in the receiver, arranged to move vertically, and as the breech-piece is opened the carrier rises to present the cartridge which it has received from the magazine to a position between the breech-piece and the open end of the barrel so that as the breech-piece is moved forward it will force the cartridge from the magazine into its place in the barrel, and when closed the breech-piece will be locked to resist the explosion. This class of arm is well known as the "Winchester" arm. In that arm a lever is arranged beneath the receiver and forms the trigger-guard. This lever is connected by toggles with the breech-piece, and also connected with the lever which operates the carrier, so that turning the lever forward the breech-piece is withdrawn, the carrier raised, returning the lever forces forward the breech-piece and drops the carrier. To conveniently operate the lever the arm is dropped from the shoulder between successive firings.

The object of my invention is to attach to this arm a slide to be operated by the left hand while the arm is at the shoulder, and through

such slide to impart to the mechanism of the arm the movements required to introduce the cartridge, remove and eject the shell; and it consists, principally, in a slide arranged beneath the barrel, and there supported so as to be moved freely toward and from the receiver in a line substantially parallel with the axis of the barrel, with an arm extending rearward therefrom and in connection with the mechanism of the gun, whereby a full reciprocating movement of said slide will impart to the mechanism of the arm substantially the same operation as does the trigger-guard lever in the Winchester arm, and as more fully hereinafter described.

A represents the receiver, which in general outline is substantially the same as that of the Winchester arm, and at the forward end of the receiver the barrel B is attached, and the magazine C arranged below it in the usual manner, both the barrel and magazine opening into a vertical recess, D, near the forward end of the receiver.

E is the breech-piece; F, the carrier; G, the carrier-lever, hung at the rear in the receiver, as at *a*, the said lever extending into recesses in the carrier, substantially the same as in the Winchester arm. The breech-piece is arranged to move longitudinally, as in that arm, and so that its rear movement will throw the hammer H to full-cock.

Hung to the breech-piece, as at *b*, is an L-shaped lever, I. One arm, J, of this lever extends rearward, and when the parts are in their normal condition stands against an abutment or shoulder, M, at the rear and serves as a brace to resist recoil. The other arm, L, extends downward.

On the pivot *a*, which is substantially the trigger-guard-lever pivot of the Winchester arm, a lever is hung, one arm, N, of which extends upward, and is constructed with a slot to engage the stud *d* on the lever L. The second arm, P, of the lever extends downward, and corresponds to the forward part of the usual trigger-guard lever.

Beneath the barrel is a slide, S, preferably arranged upon the outside of the magazine, so as to slide freely on the magazine as its guide. To the rear end of this slide a connection, T, is hinged, extending rearward, its other end

hinged to the arm P, and so that as the slide is moved forward its first action is to turn the arm or strut I upward and away from the shoulder M. Then the continued forward movement of the slide S will force the breech-piece to the rear, as seen in Fig. 2, carrying with it the hammer to full-cock. Then as the slide S is moved rearward it will draw the breech-piece to its closed position, and when arrived at that position the last part of the forward movement of the slide S will turn the strut I down into its bracing or locking position, as seen in Fig. 1.

The carrier-lever G is actuated by the turning of the lever N P, as in the turning of the trigger-guard lever in the Winchester arm, whereby after the breech-piece is opened the carrier rises, and after the breech-piece is closed the carrier is dropped. This connection of the carrier-lever with the trigger-guard lever of the Winchester arm is too well known to require detailed description in this specification.

To retract the firing-pin before the breech-piece commences its rear movement, and hold it so retracted until the breech-piece is completely closed, I form a cam-like projection, l, on the top of the strut I, which, as the strut rises, enters through a slot in the breech-piece into a corresponding cavity, m, in the firing-pin, as seen in Fig. 4, which forces the firing-pin to the rear and holds it in that position until the strut is dropped, as before described, into its locking position. Then the firing-pin is free for the action of the hammer.

The operator holding the gun at his shoulder, with his left hand upon the slide S, in the usual manner of holding a gun, after the first discharge he has only to force the slide S forward, as seen in Fig. 2, without taking the gun from the shoulder. Such forward movement draws back the breech-piece, and with it the exploded shell, which is engaged by the extractor-hook n, the same as in the Winchester arm, throws up the carrier, ejects the shell, presents a new cartridge, and then, still holding the slide S, draws it rearward to bring the parts back to their normal position, as seen in Fig. 1, which forces a new cartridge into the barrel and returns the carrier, the parts operating, as before stated, substantially as in the Winchester arm. This movement of the slide, it will be observed, is the natural movement of the left hand in the act of presenting the arm to the shoulder and taking it therefrom—that is, as the arm is brought up to the shoulder the left hand naturally comes backward beneath the gun, in which movement the parts are brought to their operating condition, and then after discharge the natural movement of the left hand is forward, and which natural movement opens the breech-piece, discharges the exploded shell, and presents a new cartridge. This arrangement, whereby the natural movement of the hand operates the mechanism of the arm, is a great advantage over the reverse action, as in other arms which are

operated by a slide beneath the barrel, as in such arrangement the forward movement of the arm at the time of preparing to fire is an unnatural one, and the rear movement of the hand after firing to open the parts is equally unnatural; but should it be desirable to arrange the slide so as to thus move forward in closing the breech-piece, and rearward in opening it, the connection T from the slide S may be made in the form of a bar, (represented in Fig. 3,) passing rearward through the receiver, as indicated in Figs. 6 and 7, and connected directly to the stud d on the arm L. The movement of the breech-piece will then be the same as before; but inasmuch as the hub of the lever N P cannot then be utilized to operate the carrier-lever G a modification of that lever will be necessary. This modification is seen in Figs. 3 and 4, and is as follows: At the rear end of the carrier-lever G an arm, e, extends upward and in the path of a stud, g, on the arm L, in its rear movement, and so that as the slide N approaches its extreme rear movement the arm L will come against the arm e and turn the lever G upward, raising the carrier, as seen in Fig. 4, substantially as before. The lever is caught in this up position by a spring-dog, R, entering a notch, f, in the lever below its pivot a, this dog being sufficient to retain the lever in its up position while the breech-piece is being moved forward and until power be applied to turn the lever. As the breech-piece approaches its forward movement the strut I is depressed, as before described, and in such depression or downward movement of the strut I it strikes an arm, h, forward of the pivot a of the lever G, and thereby forces the lever G downward, taking with it the carrier, and in this down position the lever G is caught by the spring-dog R falling into a notch, i, on the hub of the lever. In this modification I have represented the pivot on which the lever G is hung a little higher up and to the rear of the pivot of the lever N P in the first description, and this is desirable in order to the best action of the lever thus modified.

Instead of employing the vertically-reciprocating carrier, which I prefer, a vibrating carrier may be hung at the rear upon the pivot a, substantially as is the lever G, to receive the cartridge and present it to a position in front of the open breech-piece, said vibrating carrier provided with projections corresponding to the projections e h, whereby the last part of the rear movement of the breech-piece will raise the carrier, and the last part of the forward movement of the breech-piece will drop the carrier.

The arrangement of the slide S so as to be forced inward in opening the breech-piece and rearward in closing may be applied to arms having other operative mechanism—as, for illustration, many of the arms in which the mechanism is operated by a trigger-guard lever may have a connection from that lever to the slide S corresponding to the connection T

in the arm hereinbefore described, and whereby the arm will operate by the movement of the slide forward and rearward as it before was operated by the forward and rearward movement of the trigger-guard lever. I therefore do not wish to be understood as limiting this arrangement of the slide to the particular mechanism of the arm described; and instead of employing the lever L I the entire mechanism of the Winchester arm may be employed, the connection from the slide being made directly to the trigger-guard lever below its pivot.

I claim—

1. In a magazine fire-arm, the combination of the breech-piece and the carrier, with intermediate mechanism, substantially such as described, whereby as the breech-piece is opened the previously-fired cartridge is retracted and a new cartridge transferred from the magazine to a position for insertion into the barrel, with a slide arranged beneath the barrel, free for reciprocating movement in line with the barrel, and a connection between said slide, with a mechanism which operates the breech-piece and carrier, whereby the forward movement of said slide opens the breech-piece, and the return or rear movement of said slide closes the breech-piece and brings the parts to the firing condition, substantially as described.
2. In a magazine fire-arm, the combination of a longitudinally-movable breech-piece provided with an extractor-hook at its forward end, a vertically-reciprocating carrier arranged in the receiver to receive a cartridge from the magazine, a lever hung at the rear and extending forward into the receiver, through which the vertical movement is imparted to the carrier, a slide arranged beneath the barrel on guides and free for longitudinal reciprocating movement, and a connection from said slide to said lever and breech-piece, whereby the forced movement of said slide in one direction will open the breech-piece and extract the previously-exploded cartridge-shell, raise the carrier to eject the said shell, and present a new cartridge in line with the breech-piece, and moved in the opposite direction will force said breech-piece forward through the carrier to transfer the cartridge so presented to the barrel and drop the carrier, substantially as described.
3. In a magazine fire-arm, the combination of a longitudinally-movable breech-piece, a slide arranged beneath the barrel on guides and free for longitudinal reciprocating move-

ment, a lever hung to said breech-piece, one arm, I, of said lever extending rearward to form a strut to support the breech-piece in its closed position, the other arm, L, in connection with said slide, a carrier arranged to receive a cartridge from the magazine, and the lever G, hung at the rear and extending forward in connection with the carrier, and constructed with cams or projections, whereby in the rear movement said lever will be turned upward to raise the carrier, and in the forward movement said lever will be turned downward to drop the carrier, substantially as described.

4. In a magazine fire-arm, the combination of a longitudinally-movable breech-piece, a slide arranged beneath the barrel on guides and free for longitudinal reciprocating movement, a lever hung to said breech-piece, one arm, I, of said lever extending rearward to form a strut to support the breech-piece in its closed position, the other arm, L, in connection with said slide, the said strut I constructed with a cam, l, the firing-pin extending longitudinally through the breech-piece, provided with a recess, m, corresponding to said cam l, a carrier arranged to receive a cartridge from the magazine, and the lever G, hung at the rear and extending forward in connection with the carrier, and constructed with cams or projections, whereby in the rear movement said lever will be turned upward to raise the carrier, and in the forward movement said lever will be turned downward to drop the carrier, substantially as described.

5. In a magazine fire-arm, the combination of a longitudinally-movable breech-piece, a slide arranged beneath the barrel on guides and free for longitudinal reciprocating movement, a lever hung to said breech-piece, one arm, I, of the said lever extending rearward to form a strut to support the breech-piece in its closed position, the other arm in connection with said slide, and a carrier arranged to receive a cartridge from the magazine, and with extensions or projections therefrom in the path of the mechanism which imparts reciprocating movement to the breech-piece, whereby during the last part of the opening movement the carrier is raised, and during the last part of the closing movement the carrier is dropped, substantially as described.

WILLIAM MASON.
